UNITED STATES PATENT OFFICE.

CLEM CLAY BRUCE, OF MEMPHIS, TENNESSEE, ASSIGNOR OF ONE-THIRD TO LEE D. BRUCE AND ONE-THIRD TO CHARLES R. SPICER, BOTH OF MEMPHIS, TENNESSEE.

DISPLAY EASEL.

Application filed March 3, 1928. Serial No. 258,804.

The present invention relates generally to easels of the type usually employed for advertising and displaying packaged articles on the top of counters, show cases and the like.

Easels of the character above mentioned are commonly made from cardboard, and by reason of their construction are quickly affected by moisture, so that they can not be used for any appreciable length of time in certain climates, where the high degree of moisture materially shortens their life. Most easels employed for the purpose above stated have certain component parts glued or otherwise adhesively secured together, and these parts are soon affected by the moisture and caused to separate. In addition to this the entire structure when weakened by moisture readily bends under the weight of the articles supported thereby, destroying the easel for further use and making it necessary to discard the same.

It is therefore the object of the present invention to construct an easel of the class in question from a single blank of material, such as cardboard or the like, and afford said easel maximum strength and durability to withstand the effects of moisture, and thereby permit of its use in climates where other easels have been found wanting in these respects.

One of the chief characteristics of the present invention resides in the provision of an easel of the character above mentioned, wherein the main body portion is slightly bowed or curved to afford it the desired strength and durability, and thus prevent the easel from bending or flexing when used in climates having a high degree of moisture.

Another object of the invention resides in the provision of an easel wherein the main body portion is slightly bowed or curved, and additionally reinforced across its entire width to prevent bending or flexing of the easel under the conditions above outlined.

More specifically stated, the body of the easel is slightly bowed or curved to afford it additional strength and rigidity, and held in this bowed condition by interlocking flaps

arranged at one side of the easel, and which flaps are utilized to reinforce the structure in its entirety.

A further object of the invention resides in the provision of an easel with a novel construction of means for supporting the packaged articles thereon, so that the articles can not be casually separated from the easel.

Other objects and advantages will appear when the following detail description is read in connection with the accompanying drawings, the invention residing in the construction, combination and arrangement of parts as claimed.

In the drawings forming part of this application like numerals of reference indicate similar parts in the several views and wherein:

Figure 1 is a view in perspective of an easel constructed in accordance with one embodiment of the invention.

Figure 2 is a rear perspective view of the easel as illustrated in Figure 1.

Figure 3 is a sectional view on line 3—3 of Figure 1.

Figure 4 is a sectional view on line 4—4 of Figure 3.

Figure 5 is a view of the blank from which the easel is formed.

Figure 6 is a view in perspective of the same easel showing a different construction of means for supporting the packaged articles thereon.

The easel forming the subject matter of the present invention is formed from a single blank of material, preferably cardboard or the like, the main body portion of the easel being indicated at 10. It might here be stated that the easel may vary in size and configuration without departing from the inventive idea. As herein illustrated the body portion 10 is preferably of rectangular outline, and in accordance with the preferred embodiment of the invention, this body portion is cut away to provide an opening corresponding in contour to the configuration of the packaged article adapted to be supported upon the easel for the purpose of displaying and advertising said article.

In this connection it is to be noted that the body of the easel may be provided with any number of such openings, depending of course upon the size of the articles and size 5 of the easel. The material cut from the body 10 incident to the forming of the opening above mentioned is bent to provide a supporting tongue indicated at 11. This material is bent rearwardly from the lower 10 edge of the opening to form a ledge or shelf 12, from which the tongue 11 is extended upwardly at the rear of the main body portion of the easel. The packaged article 13 is partly arranged within the opening above 15 mentioned and reposes upon the ledge 12 and also rests against the supporting tongue 11. If desired the package can be secured to the tongue in any suitable manner, such as for instance by extending the tongue upwardly 20 through the wrapper of the package, or by adhesively securing the tongue thereto.

One of the chief characteristics of the present invention resides in bowing the main body portion 10 in the manner clearly illustrated in Figure 4, thus affording the easel increased strength and rigidity, as a guard against bending or flexing when the easel is used in climates having a high degree of moisture. In addition to bowing 25 the body portion 10 for this purpose, the main body portion of the easel is further strengthened and reinforced by flaps 14 and 15 respectively which extend from the opposed longitudinal edges of the body portion 10 as illustrated in Figure 5, and which flaps are adapted to be extended toward 30 each other across the entire width of the easel and interlocked in any suitable manner. The flap 14 is provided with extensions 16 35 which are adapted to be received by slots 17 provided in the flap 15. These flaps not only serve to reinforce the easel structure in its entirety, but are also used to maintain the body portion 10 in its bowed condition. 40 When the body portion 10 is bowed in this manner, the opposed edges of the package receiving opening are brought closer together, and impinge against the sides of 45 the package to assist in firmly holding the package upon the easel. An easel constructed in accordance with the present invention can not be readily or easily affected by moisture, and can therefore be used in climates where the present day easels have 50 been found wanting in these respects. The strength and stability of the easel is maintained indefinitely, so that easel can not bend or flex under the weight of the articles supported thereby when used in damp climates. It will be further noted upon inspection of Figure 3 that the package supporting tongue is arranged vertically and rests against the reinforcing flaps 14 and 55 15 after the latter have been associated, the 60 supporting tongue 11 extending a slight dis-

tance above the corresponding upper edges of the said reinforcing flaps, so that if desired this extension 18 of the tongue may be used for the purpose of attaching the article to the tongue in a manner so that the article 70 can be readily disengaged when so desired.

While any suitable means may be employed for supporting the easel upon a counter, show case or the like, I preferably employ the means illustrated in the drawings which form an integral part of the easel, and thus permit the entire structure to be formed from a single blank of material. This means consists in the use of flaps 19 and 20 respectively which project from the opposite sides of the main body portion 10 directly beneath the reinforcing flaps 14 and 15 as clearly shown in Figure 5. The flaps 19 and 20 are extended rearwardly in convergent relation, each flap being formed 85 with a tongue 21, which tongues are interlocked as illustrated in Figure 4, thereby holding the flaps 19 and 20 associated and positioned relatively to form a supporting base for the device. 90

The packaged articles may be supported upon the easel in various other ways without departing from the inventive idea, and in Figure 6 I have illustrated a modified form of the invention wherein the body portion 10 is provided with spaced pairs of openings 22, each pair of openings being used in conjunction with a suitable clamping band 23 which is adapted to embrace the packaged article 24, and have its ends 95 passed through the particular pair of openings 22 and secured to the body of the easel in any suitable manner. The structure shown in Figure 6 is identically the same as that described in connection with the other 100 figures in the drawings. 105

While it is believed that from the foregoing description, the nature and advantages of the invention will be readily apparent, I desire to have it understood, that I 110 do not limit myself to what is herein shown and described and that such changes may be resorted to when desired as fall within the scope of what is claimed.

What is claimed is:

1. A display easel formed from a single blank of material and including a bowed body portion upon which packaged articles are adapted to be supported, interlocking reinforcing flaps extended from the edges of the body portion and wholly arranged at one side thereof, maintaining the body portion in its bowed condition, and interlocking flaps projecting rearwardly from the body portion beneath the first mentioned flaps and constituting a supporting base for the easel. 115
2. A display easel formed from a single blank of material and including a bowed body portion cut away to provide an article receiving opening and a flap at each side 120
3. A display easel formed from a single blank of material and including a bowed body portion upon which packaged articles are adapted to be supported, interlocking reinforcing flaps extended from the edges of the body portion and wholly arranged at one side thereof, maintaining the body portion in its bowed condition, and interlocking flaps projecting rearwardly from the body portion beneath the first mentioned flaps and constituting a supporting base for the easel. 125
4. A display easel formed from a single blank of material and including a bowed body portion cut away to provide an article receiving opening and a flap at each side 130

edge of the body portion, the free ends of the flaps having means whereby they can be locked together to hold the body portion bowed, the material separated from the body portion in the formation of the opening being extended rearwardly to form a ledge and thence upwardly to form an article supporting tongue arranged in spaced parallel re-

lation to the opening, said tongue resting against the flaps and having a reduced upper end which extends a slight distance above the flaps whereby an article supported by the ledge can be fastened to said upper end. ¹⁰

In testimony whereof I affix my signature.

CLEM CLAY BRUCE.
